ORTHODONTIC APPLIANCE

Filed Oct. 28, 1929

INVENTOR:—
SPENCER R. ATKINSON
BY *Martin J. Smith* ATTY.

UNITED STATES PATENT OFFICE

SPENCER R. ATKINSON, OF PASADENA, CALIFORNIA

ORTHODONTIC APPLIANCE

Application filed October 28, 1929. Serial No. 402,954.

My invention relates generally to orthodontic appliances and more particularly to a bracket that is secured to the tooth band and which bracket serves as a point of attachment or anchorage for the arch-bow or wire and the tang or tie wires and springs that are utilized in connection with the tooth band and arch-bow or orthodontic devices.

The principal objects of my invention are, 10 to generally improve upon and simplify the construction of the existing forms of the brackets that are utilized upon the tooth bands or ribbons or orthodontic devices, further, to provide a bracket having means 15 for receiving and anchoring the tang or tie wires and the springs that are sometimes utilized in connection with the arch-bow for the adjustment and correction of the dental arch and further, to provide an orthodontic 20 bracket of the character described, that is relatively simple in construction, inexpensive of manufacture, capable of being readily combined with the standard forms 25 of orthodontic appliances now in general use, and further, to provide a bracket that will be highly effective in performing the functions for which it is intended.

With the foregoing and other objects in view, my invention consists in certain novel 30 features of construction and arrangement of parts that will hereinafter be more fully described and claimed and illustrated in the accompanying drawings, in which:

Fig. 1 is a perspective view showing a 35 portion of a tooth band or ribbon and showing a bracket of my improved construction in position for use upon said band.

Fig. 2 is a front elevational view of the bracket in position upon the band and showing the arch-bow and the tang or tie wire connected to said bracket.

Fig. 3 is a cross section taken on the line 3-3 of Fig. 2.

Fig. 4 is an elevational view of my improved bracket in position upon the tooth band and showing a spring connected to said bracket and bearing on the arch-bow or wire.

Fig. 5 is a perspective view of a modified 50 form of the bracket.

Fig. 6 is a front elevational view of a modified form of the bracket and showing the same in position upon the band.

Fig. 7 is a cross section taken on the line 7-7 of Fig. 6.

Fig. 8 is an elevational view of a modified form of the bracket.

Fig. 9 is a top plan view of a further modified form of the bracket.

Fig. 10 is an elevational view of the form 60 of bracket that is illustrated in Fig. 9.

Referring by numerals to the accompanying drawings and particularly to the construction illustrated in Figs. 1 to 3 inclusive, 10 designates the band and rigidly fixed to the outer face thereof in any suitable manner is a thin reenforcing plate 11.

Rigidly secured to this reenforcing plate 65 is the bracket 12 contemplated by my invention and which bracket is formed from strong, tough, rigid metal such as platinum or composition metal having platinum incorporated therewith.

The body of metal that forms the body 75 of the bracket is arranged with its greatest length vertically disposed on the reenforcing member 11 and the upper inner portion of the bracket is cut away to form a transverse notch 13 that is adapted to receive the arch-bow or wire and which latter may be of any desired form in cross section, either round, square or polygonal.

Formed in the lower portion of the body 80 of the bracket and extending inwardly from the front face thereof is a horizontally disposed notch 15 that is adapted to receive a tang or tie wire or a portion of a spring and which parts are associated with the arch-bow and the band when the appliance is 85 fitted into the dental arch.

This notch 15 extends to the inner or rear wall of the notch and after the arch-bow, such as A, and the tang or tie wire, such as T, are properly located in their respective notches, a key or locking pin such as K, is inserted downwardly through the opening in the bracket in front of the arch-bow or wire and the tang or tie wire and the projecting lower end of said key is bent upwardly against the underside of the bracket, 95 100

thereby firmly securing the parts in assembled relation (see Figs. 2 and 3).

The tang or tie wire, which is connected to the lower portion of the bracket 12, functions in cooperation with the arch-bow in imparting vertical, lateral, or tortional stresses to selected teeth of the dental arch for the purpose of correcting the irregularities thereof, and finally aligning the teeth 10 into the correct dental arch and further, said tang or tie wire may be utilized for preventing the drift of a tooth while the same is being forced deeper into the gum.

In Fig. 4 I have shown yielding pressure means associated with the bracket and arch-bow for imparting pressure to the engaged tooth so as to swing the same laterally in either direction and such construction includes a spring 16 formed from a short section 20 of resilient wire, one end of which occupies the rear portion of the notch 15 and being retained therein by the key K and said spring extends downwardly, thence laterally beneath the underside of the bracket, thence 25 upwardly and the end of this spring is formed into a hook 17 that engages over the arch-bow A. Obviously this spring may be arranged on either side of the bracket so as to swing the tooth laterally in the desired 30 direction.

Secured in any suitable manner on the arch-bow or wire is a collar 18 that functions as a stop against which the upper end of spring 16 engages, and thus the strains and 35 stresses developed by said spring and imparted to the band and the tooth that the latter encircles may be accurately regulated and controlled.

In the modified construction illustrated in 40 Fig. 5, the lower portion of the bracket is provided with a transversely disposed aperture 19, which may be either round or rectangular and which is of sufficient size to accommodate the tang or tie wire T.

In Figs. 6 and 7 I have disclosed a further modified arrangement for receiving and anchoring the tang or tie wire and this construction comprises a short cylindrical member 20 that is rigidly secured in any suitable manner in the corner between the underside of the bracket 12 and the outer face of the band 10. When this form of device is used, the tang or tie wire T is threaded 55 through the tubular member.

In Fig. 8 a further modified construction is illustrated and such construction comprises a short tubular member 21 that is secured in position in the corner between one of the side faces of the bracket 12 and the 60 front face of band 10.

In Figs. 9 and 10, I have illustrated a modified form of the spring arrangement between the bracket and arch-bow and in this construction the central portion of a 65 piece of resilient wire is bent to form a coil

22 that occupies a horizontally disposed position on top of the arch-bow at the point where the same passes through the bracket and one end of the spring extends from said coil laterally and downwardly and the end 70 of this portion of the spring is formed into a hook 23, that engages beneath the arch-bow at a point adjacent to one side of the bracket.

The other portion of the spring extends 75 downwardly through the bracket and its end is bent beneath the underface of the bracket, thus retaining the spring in assembled relation with said bracket and the arch-bow. Obviously the form of spring just described 80 may be used on either side of the bracket.

Thus it will be seen that I have provided a relatively simple, practical and inexpensive bracket that is especially designed to be applied to the tooth encircling bands of 85 orthodontic appliances and which bracket provides a convenient support and point of attachment for the tang or tie wires and springs that are utilized in connection with the arch-bow for the purpose of applying 90 the desired strains and stresses to the teeth, so as to produce the correct dental arch.

It will be understood that minor changes in the size, form and construction of the various parts of my improved orthodontia 95 appliances may be made and substituted for those herein shown and described without departing from the spirit of my invention, the scope of which is set forth in the appended claims.

I claim as my invention:

1. An orthodontic appliance, comprising a bracket, there being an arch-bow receiving notch formed in the upper inner portion of said bracket, the lower front portion of said bracket being provided with a wire receiving opening and said bracket being provided with a vertically disposed opening that intersects said arch receiving notch and said wire receiving opening.

2. In an orthodontic appliance, the combination with a tooth band of a bracket secured on said band, an arch-bow passing through the upper portion of said bracket, there being a transversely disposed opening formed in the lower front portion of said bracket, a wire passing through said opening and there being a vertical opening formed through said bracket in front of said arch-bow and wire.

3. In an orthodontic appliance, the combination with a tooth band of a bracket secured on said band, an arch-bow passing through the upper portion of said bracket, there being a transversely disposed opening formed in the lower front portion of said bracket, a wire passing through said opening, there being a vertically disposed opening formed through said bracket in front of said arch-bow and wire and means passing 130

through said vertical opening for securing the arch-bow and said wire to said bracket.

4. In an orthodontic appliance, the combination with a tooth band of a bracket secured to said band, there being an arch-bow receiving opening in the upper rear portion of said bracket, an arch-bow passing through said opening, there being a transverse opening formed in the lower portion of said bracket, said bracket having a vertically disposed opening that intersects said arch bow receiving opening and said transverse opening, a spring having one end positioned in the opening in the lower portion of said bracket and the opposite end of which spring engages the arch-bow that is seated in said bracket.

5. In an orthodontic appliance, the combination with a tooth band of a bracket secured to said band, there being an arch-bow receiving opening in the upper rear portion of said bracket, an arch-bow passing through said opening, there being a transverse opening formed in the lower portion of said bracket, said bracket having a vertically disposed opening that intersects said arch-bow receiving opening and said transverse opening, a spring having one end positioned in the opening in the lower portion of said bracket, the opposite end of which spring engages the arch-bow that is seated in said bracket and means seated in the vertical opening in said bracket for securing the arch-bow and spring to said bracket.

35 6. In an orthodontic appliance, the combination with a tooth band of a bracket secured to said band, there being an arch-bow receiving opening in the upper rear portion of said bracket, an arch-bow passing through said opening, there being a transverse opening formed in the lower portion of said bracket, said bracket having a vertically disposed opening that intersects said arch-bow receiving opening and said transverse opening, a spring having one end positioned in the opening in the lower portion of said bracket, the opposite end of which spring engages the arch-bow that is seated in said bracket, means seated in the vertical opening in said bracket for securing the arch-bow and spring to said bracket and means on the arch-bow for engaging the end of the spring that engages said arch-bow.

7. As a new article of manufacture, an orthodontic appliance comprising a substantially rectangular bracket provided in its upper rear portion and its lower front portion with transversely disposed openings and said bracket being provided with a vertically disposed key receiving opening that intersects said transversely disposed openings.

In testimony whereof I affix my signature.

SPENCER R. ATKINSON.
